UNITED STATES PATENT OFFICE.

ALFRED S. ORCHARD, OF PHILADELPHIA, PENNSYLVANIA, ASSIGNOR TO KEYSTONE TYPE FOUNDRY, OF PHILADELPHIA, PENNSYLVANIA, A CORPORATION OF PENNSYLVANIA.

PRINTER'S GALLEY.

1,142,200.

Specification of Letters Patent.

Patented June 8, 1915.

Application filed August 1, 1914. Serial No. 854,550.

To all whom it may concern:

Be it known that I, ALFRED S. ORCHARD, a citizen of the United States, residing at Philadelphia, Philadelphia county, and 5 State of Pennsylvania, have invented and discovered certain new and useful Improvements in Printers' Galleries, of which the following is a specification.

My said invention consists in certain improvements in the construction and arrangement of parts of printers' galleries, whereby 10 an article of this character is provided which is comparatively inexpensive, but at the same time rigid, accurate in form and 15 durable, all as will be hereinafter more fully described and claimed.

Referring to the accompanying drawings, which are made a part hereof and on which similar reference characters indicate similar 20 parts, Figure 1 is a perspective view of the rim or sides of the gallery as it appears before bent into form for use, Fig. 2 a perspective view of said rim bent into gallery form and also showing the bottom or floor of the 25 gallery separate therefrom, Fig. 3 a perspective view of the parts shown in Fig. 2 assembled, and Fig. 4 a detail section through one side of the gallery to illustrate the construction more clearly.

30 In said drawings, the portions marked A represent the rim or side frame of the gallery and B the bottom thereof.

The rim A is in one piece and of the form clearly shown in the drawings, being in 35 effect of a channel-iron shape on its outside with the lower flange 10 doubled and its under part extending inward beyond the inner face line of the rim to afford a support for the floor of the gallery. The space between the two parts of this double flange is 40 of a width corresponding to the thickness of said bottom so that the bottom can slide into the groove thus formed with a close fit. The upper flange 11 is for the purpose of 45 lending rigidity or stiffness to the sides of the gallery. Said side piece or rim is formed of a single piece of appropriate metal, rolled or stamped out with appropriate dies, and having notches α and β through the flanges 50 10 and 11, to permit the rim to be easily and truly bent at these points to bring the portion between the point α and β at right angles with the portions on each side thereof.

The inner face of said rim is straight, plumb with the floor and smooth to afford suitable 55 support for the type.

The floor B is a metal plate of appropriate form and after being slid into place in the groove formed by the flange 10 of the rim A, is secured by being spot-welded, soldered, 60 riveted, or secured in any other approved manner. When thus secured the whole structure is very solid and rigid and at the same time comparatively inexpensive.

Having thus fully described my said invention, what I claim as new and desire to secure by Letters Patent is:

1. A printer's gallery comprising a rim formed of a single piece of metal having outwardly extending flanges at its top and 70 bottom edge, the lower flange being doubled with a groove between its two parts to receive the floor of the gallery and said flanges being cut out at points corresponding to the corners of the back of the gallery and bent 75 with the parts outside of said cut-out portions at right angles to the part between said cut-out portions, a floor consisting of a metal plate inserted in the groove in said lower flange of the rim and rigidly secured therein, substantially as set forth. 80

2. A printer's gallery comprising a one-piece rim bent into appropriate form and having outwardly projecting flanges at its upper and lower edges, the lower flange being formed doubled with a groove between the two parts thereof, and a floor plate mounted in said groove and secured to said rim, substantially as set forth. 85

3. A printer's gallery comprising a one-piece rim bent into appropriate form and having outwardly projecting flanges notched at the bends in said rim, the lower flange being formed doubled, and a floor plate secured in the groove between the two parts 95 of said lower flange, substantially as set forth.

In witness whereof, I have hereunto set my hand and seal at Philadelphia, Pennsylvania, this 8th day of July, A. D. nineteen 100 hundred and fourteen.

ALFRED S. ORCHARD. [L. S.]
